UNITED STATES PATENT OFFICE.

ARTHUR C. BULLEN, OF SWINK, COLORADO.

VEGETABLE-CUTTER.

1,220,179.

Specification of Letters Patent.

Patented Mar. 27, 1917.

Application filed December 5, 1916. Serial No. 135,118.

To all whom it may concern:

Be it known that I, ARTHUR C. BULLEN, a citizen of the United States, and a resident of Swink, in the county of Otero and State 5 of Colorado, have invented a certain new and useful Improvement in Vegetable-Cutters, of which the following is a full, clear, and exact description.

My invention is an improvement in cutting machines for vegetables or the like, and it is particularly adapted for use in making potato chips and "shoe-string" potatoes, in which preferred embodiment I have elected to illustrate it. The principal objects of 10 my invention are to produce a device especially adapted for household use in that it has a minimum number of parts, is cheap and economical to make, easy to clean and presents the minimum of danger of accident. 15 Further and more particular objects and advantages of my invention will later appear in this specification.

In the single sheet of drawings accompanying this application and forming a part hereof

Figure 1 is a rear elevation of my device;

Fig. 2 is a central, vertical section through the same, the crank shaft and clamping 30 stand appearing in elevation;

Fig. 3 is a side view on a larger scale of a form of knife adapted to produce "shoe-string" potatoes;

Fig. 4 is a partial plan view of the knife 35 shown in Fig. 3; and

Fig. 5 is a partial perspective view of a form of blade adapted to produce potato flakes.

Referring in detail to the drawings, in 40 which like characters of reference indicate like parts in the several figures, it will be seen that the main portion of my device comprises a casing (preferably cast), in the form of an open-ended, horizontal cylinder 10 provided with a feed hopper 11 and a supporting stand 12 which has clamping jaws 13, in one of which there is a clamping screw 14 by which the device may be conveniently mounted on a table or the like. 45 The rear side of the cylinder 10 is provided with a three-arm spider 15, and within the interior of the casing 10 there is formed an inclined disk 16 between the edges of which and the inner side of the cylinder 10 there

is provided clearance on all sides. This inclined disk 16 is supported at two points; on the lower side it has its support where the lip 17 has contact with the outer edge of the cylinder 10, and at its upper side the inclined disk 16 is supported by a horizontal arm 17^a integral therewith and with the vertical member of the spider 15.

The cutting knives of my device are carried in slots in the outer surface of a cylindrical drum 18, which is open at the rear and closed at the front and which drum is rotatable within the previously mentioned clearance. The drum 18 is mounted on a shaft 19, which shaft is journaled at the rear in a bearing 20 carried by the spider 70 15 and at the front in a sleeve 21 formed as a forwardly projecting extension of the inclined disk 16. The shaft 19 is squared at 22 where it passes through a similarly shaped opening in the hub 23 on the drum 75 18, thus insuring that shaft and drum will rotate together. A pin and collar 24 on the rear of the shaft 19 holds the parts removably in place and the shaft 19 is formed with a crank 25 and handle 26 for imparting a 80 rotating motion to the drum 18.

In Figs. 1 and 2 I have illustrated my device as equipped with the serrated knives for making "shoe string" potatoes. These knives are shown in detail in Figs. 3 and 4 85 and comprise a reduced shank 27 having screw holes 28 therein. The other ends of the knives, which form the cutting surfaces, are formed into convolutions having serrated cutting surfaces 30. The surface of 90 the drum 18 is cut out, as illustrated in Fig. 1, at a plurality of places to provide locations where the knives may be inserted. To the rear of each of these cut out portions the drum is notched (as shown in 31) to 95 form a shoulder upon which the reduced portions 27 of the knives may rest and with screw holes registering with holes 28 in which screws 32 may be received to secure the knives in position. The relative locations of the convolutions 29 and cutting edges 30 on successive knives are preferably staggered so as to insure that one knife will strike the vegetable being cut, not in the grooves left by the preceding knife, but instead on the projections left by the previous cut.

In Fig. 5 I have illustrated a plain knife

adapted to forming flakes or chips which may be substituted for the knives shown in Figs. 3 and 4 in a manner perfectly obvious.

The manner of operation of my device will be obvious from the foregoing description of its parts. The vegetables to be cut are fed in the hopper 11, which, it will be noticed, is located off center and has its lowest point 33 in the direction of rotation 10 of the drum. The vegetables lying in the hopper 11 are contacted by the knives and sections of the same are pared off. These removed portions pass through the openings 34 in the drum which are just in advance of 15 the knives and lodge on the inclined surface of disk 16 whence they will slide down off the lip 17 into a receptacle placed thereunder. The wedge-shape given to the portion 33 of the hopper, together with the 20 crowding action incident to the rotation of the drum, will insure that the vegetables in the hopper will press against the knives and the slight lip 35 provided at its lowest edge will serve to retain small remaining particles so that all may be suitably cut.

It will be obvious that if found more convenient in casting the inclined disk 16 may be formed separate from the cylinder 10 and held in place by a groove and tenon or other 30 connection at X and by a lip or the like at Y; and that this and other changes in details of construction may be made without departing from my invention. I do not, therefore, desire to be considered as limited 35 to the precise details shown and described but may alter my device within the limits of the appended claims.

Having thus described my invention, what I claim and desire to secure by Letters Patent is:

1. In a device of the class described, an open-ended casing provided with a hopper and having a spider at one end thereof, an inclined disk within said casing and spaced 45 from the walls thereof, a drum rotatably mounted within said casing and surrounding said disk, a shaft upon which said drum is mounted, said shaft being journaled in

said spider and in said disk, cutting knives mounted on the outer surface of said drum, 50 and means for rotating said shaft.

2. In a device of the class described, an open-ended horizontal casing provided with a hopper and having a spider at the rear end thereof, an inclined disk within said casing and spaced from the walls thereof, 55 said disk extending substantially from the upper front side to the lower rear side of said casing, a drum rotatably mounted within said casing and extending from front to rear thereof and surrounding said disk, a shaft upon which said drum is mounted, said shaft being journaled in said spider and in a bearing carried by said disk, cutting knives mounted on the outer surface of said 65 drum, and means for rotating said shaft.

3. In a device of the class described, an open-ended casing provided with a hopper and having a spider at the rear end thereof, an inclined disk within said casing and 70 spaced from the walls thereof, a drum rotatably mounted within said casing and surrounding said disk, said drum being open on its rear side and closed on its front side, a shaft upon which said drum is mounted, 75 said shaft being journaled in said spider and in said disk, cutting knives mounted on the outer surface of said drum, and means for rotating said shaft.

4. In a device of the class described, an open-ended cylindrical casing provided 80 with a hopper and having a spider at one end thereof, an inclined disk within said casing, said disk being spaced from the cylindrical walls of said casing and supported 85 independently of said cylindrical walls, a drum rotatably mounted within said casing and surrounding said disk, a shaft upon which said drum is mounted, said shaft being journaled in said spider and in said disk, 90 cutting knives mounted on the outer surface of said drum, and means for rotating said shaft.

In testimony whereof I hereunto affix my signature.

ARTHUR C. BULLEN.
